ANTI-SWAY LINKAGE FOR CONTAINER
ENGAGING MEANS
George P. Hurst, 719 Northampton Ave.,
Palo Alto, Calif.
Filed June 26, 1963, Ser. No. 290,811
4 Claims. (Cl. 212—129)

This invention relates to apparatus for lifting and for transferring containers from land or water vehicles to another point and for accurately depositing such containers at such point in a predetermined position at an angle to the position of the containers when lifted.

In the freight transporting business, whether by land or water, every effort has been made in recent years to handle the freight or cargo more efficiently. These efforts have resulted in the shipping of freight and cargo in large containers that have reached substantially the size of the box or body portion of standard oblong freight cars that are approximately forty feet in length, horizontally, approximately eight feet in width and between thirteen and fourteen feet in height. Their capacity may be as high as forty tons.

In marine shipping similar containers may be employed, although usually they are smaller, and their capacity may be approximately twenty tons.

In a freight distributing center at a railway terminal there are usually a plurality of pairs of parallel tracks in side by side relation alongside or parallel with, or between, loading platforms. One of the difficulties in unloading containers from and loading them on such cars by overhead portable cranes or hoists is that of supporting the hoist or crane in a position to selectively remove containers from any of the rows of railway cars that may be on said tracks, or to load any of such cars.

Another appreciable difficulty heretofore encountered is an efficient and economical structure that will enable lifting the containers and carrying them free from objectionable swinging of said containers under the influence of inertia or the wind.

A still further difficulty is presented in efficiently and quickly positioning the containers. In freight yards the land trailers intended to receive the containers from the cars have heretofore been positioned at an angle of approximately ten to twenty degrees relative to the railway tracks in order to position as many trailers as possible along the tracks, although many more trailers could be positioned along the tracks if the longitudinal axes of the trailers could be at right angles to the length of the track.

With the present invention containers may be quickly and selectively loaded and unloaded from cars in any of the adjacent parallel tracks alongside a loading or unloading area or platform, and also the containers will each automatically swing to a position substantially at a right angle to the tracks during transfer from the cars to the loading or unloading area, and furthermore the containers will be elevated by cable hoists but held against objectionable swinging during transit.

It is one of the objects of the invention to provide apparatus that will accomplish any of said above results or all of them.

Another object of the invention is the provision of a container hoist that is adapted to transfer containers from the freight cars to an unloading area, and vice versa, in which the containers may be swung to position either end in one of two opposite directions when loaded onto the car or when unloaded and deposited at the loading area or vice versa.

It may be pointed out that at the present time special cargo ships have been designed to receive the large, horizontally elongated containers with overhead cranes

2

mounted on tracks on the weather deck extending along the gunwales to move longitudinally of the ship for carrying containers to and from the different holds. Trailers alongside the ship and on the dock are in positions similar to trailers alongside a railway station to receive the containers, or from which the containers are removed for loading onto the ships. The present invention is applicable to this arrangement.

Other objects and advantages will appear in the description and drawings, in which:

FIG. 1 is a top plan view of a railway distributing point at an unloading area showing the present invention in semidiagrammatic form at such point.

FIG. 2 is a side elevational view of the arrangement shown in FIG. 1 as seen from line 2—2 of FIG. 1 in which the unloading device is indicated at the right hand side in full line in elevated position with a conventional railway car container carried thereby and in dot-dash lines at the left side of the view that container and hoisting means are shown in a position for lowering the container onto a road vehicle or platform.

FIG. 3 is an enlarged part elevational, part sectional view of the hoisting apparatus, taken generally along line 3—3 of FIG. 1. The hoisting means is in lowered position.

FIG. 4 is an end elevational view of the hoisting apparatus as seen from line 4—4 of FIG. 3 except that the supporting trolley wheels are omitted.

FIG. 5 is an end elevational view of the apparatus shown in FIG. 4, but in a collapsed position.

FIG. 6 is a vertical sectional view taken along line 6—6 of FIG. 3 showing the means for actuating the load engaging elements.

FIG. 7 is an enlarged elevational view of the trolley portion supporting the carriage, including one of the driving means, the carriage being in the dotted line position at the left end of FIG. 1, which carriage is shown in full line in the right hand portion of FIG. 1.

FIG. 8 is a cross sectional view taken at a right angle to the view of FIG. 7.

FIG. 9 is a reduced size, simplified top plan view similar to FIG. 1, but which arrangement enables loading and unloading at either of two opposite sides of a track or set of tracks.

FIG. 10 is a reduced size top plan view similar to FIG. 9 which is adapted to operate in substantially the same manner as the arrangements shown in FIG. 9 except that the containers lifted off the cars will always be turned the same way over each of the loading and unloading platforms.

FIG. 11 is a simplified side elevational view showing a structure in which part of that shown in FIGS. 5, 10 may be eliminated where the containers are lifted only a relatively short distance.

55 In its broadest aspect, the present invention may be said to be a gantry type travelling crane incorporating a cantilever feature in that it comprises overhead tracks supporting a carriage for movement horizontally from positions between a pair of opposed wheel mounted supports that support the tracks in elevated position, and the latter project past one of the said supports so the carriage may move past the pair of supporting frames to at least one side thereof.

FIG. 1 which is a top plan view shows a pair of horizontally extending overhead tracks 1, 2 that are supported in elevated position by any suitable frame 3. Such frame includes vertically disposed legs or supports 4, each of which may be mounted on wheels 5 that, in turn, roll on parallel, horizontally extending rails 6 for movement of the frame 3 and the tracks 1, 2 longitudinally of the rails and transversely of the tracks 1, 2.

Said tracks 1, 2 are carried below horizontal cross

frame members 7 that, in turn, may be connected by upper side frame members 8. The spacing between the legs at the side of crane frame from which the tracks 1, 2 project must be sufficient to enable the container to pass therebetween, as will later appear.

The spacing between the opposed supports between which tracks 1, 2 extend may vary according to the number of sets of railway rails 9 to be spanned. In FIG. 2 there are three sets of rails 9, which is merely illustrative, since there may be more or less.

In the event an elevated loading and unloading platform 10 is along one of the sides of the sets of said rails 9, as seen in FIG. 2, one of the rails may be supported in a groove or recess 11 in the platform so that the upper surface of the rail 6 is substantially flush with the upper surface of the platform, and such a recess is preferable in any event so that the rail 6 will not be an obstacle to the passage of vehicle wheels thereover.

Motor powered wheels supporting gantry cranes are old, and in the present instance one of the wheels 5 at each side of the crane may be connected by any suitable power driven means generally designated 15 (FIG. 2) with a source of power for moving the crane in one direction or the other on rails 9.

Tracks 1, 2 are spaced apart a substantial distance and are parallel where they extend over the rails 9, and then they curve toward each other to form an intermediate section 16 in continuation of one of the ends of the rail crossing portions where they pass under the cross frame member 7, after which they again extend parallel and close together to form an outwardly projecting end portion generally designated 17.

This arrangement of tracks 1, 2 is generally the same as shown in U.S. Letters Patent No. 3,047,159 that issued July 31, 1962 to myself and Mowatt M. Hurst, except in that instance the tracks were relatively short at their widely spaced end portions, whereas in the present instance, the widely spaced end portions are relatively long.

Suspended from track 1 is a horizontally elongated beam 18 (FIGS. 4, 5, 7) and two pairs of trolley wheels 19 at each of the opposite ends thereof support said beam from track 1, said wheels rolling on the opposingly outwardly projecting lower flanges 21 of track 1, the latter being an I-beam in cross sectional contour. FIGS. 7, 8 show each set of four wheels arranged in two opposed pairs rotatably supported on the ends of the arms of a pair of inverted yokes generally designated 25. A head 26 secured between yokes 25 connects the lower ends of the yokes, and each head is swivelly connected with one of the ends of beam 18 so that the ends of said beam are swivelly suspended from said heads.

A vertical shaft or pivot 28 intermediate the ends of beam 18 swivelly connects the beam 18 with one end of a horizontally disposed carriage 29 (FIG. 7).

The opposite end of said carriage is swivelly suspended below track 2 and from said track 2 by wheels 30, beam 31, yokes 32, and heads 34 that correspond to wheels 19, beam 18, yokes 25 and heads 26. The pivot 28 from which the one end of carriage 29 is suspended from track 1 is below track 1 when the sides of the lateral carriage are parallel with the tracks of portion 17 and at that time the pivot 33 from which the opposite end of the carriage is suspended is below track 2. The purpose of this, as will later appear, is to insure the carriage 29 being at a right angle to the rails 9 when the carriage is suspended from track lengths 17.

The tracks 1, 2, as seen in FIG. 1, provide what may be generally called a Y pattern, having a leg portion 17 and two arms extending generally divergently from the leg, except when their outer end portions are parallel. Carriage 29 when in a position suspended below the leg portion has its longitudinal axis parallel with said leg, and said carriage is suspended at one end from track 1 and at the other end from track 2.

Upon moving the carriage 29 from the leg of the Y

onto the arms of the tracks 1, 2 the carriage will automatically swing to a position at a right angle to the leg 17. The reverse will automatically occur in moving the carriage from the arms onto the Y.

Various means may be employed for moving the carriage, one of which is described in the patent already mentioned, and which would be suitable where the same end of the carriage will always lead the other in moving from the arms of the Y onto the leg portion. The means for connecting the carriage to the container to be lifted will be explained more in detail later on, but at this point, it is sufficient to know that the containers usually are long and each is suspended from the carriage with the longitudinal axis parallel with the axis of the carriage, and it will swing as a unit with the carriage.

In FIG. 1 a plurality of containers or trailers 35 are indicated on rails that are alongside and parallel with the loading and unloading platform. The arms of the overhead Y tracks extend over the containers 35 at right angles to the longitudinal axes of said containers. The leg 17 of the Y extends over the loading platform on which may be the trailers onto which the containers are to be loaded, or the containers may be on the platform or on trailers that are on the latter, and the freight cars will be on the rails 9. However, assuming the first situation with the containers on the freight cars, the carriage 29 will be moved to a position over the container to be unloaded, as indicated in FIG. 1.

In the present invention I provide means for moving opposite ends of the carriage 29 at the same rate of speed when the carriage is on the arms of the overhead Y support and at a right angle to the latter, and part of the same means is adapted to positively drive one end or the other, as desired, along the curved portions of tracks 1, 2 and along the leg of the Y.

One means for moving the carriage is illustrated in FIGS. 7, 8 in which a rack 40 (FIG. 7) is secured to the track 1 at the side of the web 41 of said track that faces outwardly relative to track 2. This rack is positioned in a laterally opening channel, the upper side of which is the upper flange 42 (FIG. 8) and a horizontally disposed strip 43 spaced below and parallel with said flange. Said rack extends longitudinally of the track 1.

Supported by a bracket 44 on the head 26 on the yokes 25 at one of the sets of wheels 19 is an electric motor 45 that is operatively connected with a gear 46 through any suitable gear box. Gear 46, in turn, has its teeth in mesh with the teeth of rack 40. The motor 45 is reversible to drive the end of the carriage connected with beam 18 in one direction or the other.

Identically the same driving means is carried by one of the heads on yokes 32 that carries beam 31. The track 2 carries a rack on its side that faces away from track 1, which rack is identical with rack 40.

In FIG. 1 the driving mechanism above described on beam 18 is generally designated 50 while the driving mechanism that is associated with beam 31 is generally designated 51.

It should also be noted that each of the yokes 25, 32 carries a roller 52 positioned below each of the tracks 1, 2 (FIG. 7) adapted to engage the tracks, should there be any upward movement of the yokes, and also each beam rotatably supports rollers 53 that are adapted to engage a horizontal top plate 54 on each end of the carriage 29 to stabilize the carriage during and after swivelling movement of the carriage (FIG. 8).

The motors controlling the movement of the gantry crane as a unit and for controlling each of the motors 45 may be operated from a single control unit positioned within the operator's cage 54' (FIG. 2) that is on the crane and above the tracks from which point all loading and unloading operations may be observed, or at any other desired point, and the conventional safety limit switches may be positioned along the tracks to prevent accidental operation of the motors 45, such as causing the carriage

to move beyond its maximum safety limits on the tracks, and to prevent simultaneous movement of the motors during the swivelling of the carriage when the latter is suspended from the intermediate portions 16 of the tracks.

One of the main features of the present invention is the provision of reliable, simple, and economically made means for stabilizing the containers during lifting and lowering thereof, and during swivelling at portions 16 of the tracks 1, 2 and also during movement of the containers and during stopping thereof.

Supported at one end of the carriage for rotation about a common axis are winding drums 55 (FIG. 1) driven in one direction or the other by a reversible electric motor 56 (FIG. 3) that is carried by said carriage. Two cables 57 extend downwardly from said drums adjacent to the corners of the carriage at one end thereof, while two other cables 58 extend from drums 55 horizontally to the opposite end of the carriage where they extend over sheaves 59 adjacent to the corners of the carriage at said opposite end, and downwardly.

One of the cables 57, 58 at one side of the carriage connect at their lower ends with opposite ends of a container engaging lifting bar 60 while the cables 57, 58 at the other side of the carriage connect at their lower ends with the opposite ends of a second lifting bar 60 that is identical to the first. The pair of bars 60 have flanges 61 that extend toward each other to engage below each container 35, each container having an elevated ledge along its lower side for engagement by such bars, this feature in itself being conventional.

Bars 60 are parallel and at the same level, hence upon actuation of the motor 56 to rotate drums 55 in one direction the bars will be simultaneously elevated at the same rate of speed, and upon rotation of the drums 55 in an opposite direction, the bars will be lowered at the same rate of speed.

Two pairs of links 63, 64 (FIG. 3) of the same length are pivotally connected at one of their ends with the opposite ends of each lifting bar 60 for swinging of said links vertically in substantially the same plane and which is substantially the plane in which each lifting bar is disposed. The pairs of links 63, 64 on each bar 60 extend upwardly and toward each other from the ends thereof that are pivotally connected to each bar, and the upper ends of said pairs of links are pivotally connected by pivots 65 with the lower ends of a pair of links 66, 67. The links 66, 67 of each pair are the same, and the lower ends of links 66, 67 are between the upper ends of each pair 63, 64 (FIGS. 5, 6) while the vertical flange 68 of each lifting bar 60 is between each pair of links 63, 64. The upper ends of links 66, 67 are pivotally connected by pivots 69 with the lower ends of vertically extending bars 70. Said bars 70 are split at their lower ends for a substantial distance to form a clevis 71 into which the flat-sided upper ends of links 66 are positioned. The axes of pivots connecting the lower ends of the links 64 with flange 68 of the lifting bars and the axes of pivots 65, 69 are parallel and at right angles to the length of carriage 29, hence they are adapted to swing in a plane that is parallel with each side of the carriage from a position in which the links 63-67 are extended to an extended position in which the lifting bars 60 are adapted to engage below a container 35 to a collapsed position in which the links 63-67 are horizontally extending and almost parallel to each other.

The bars 70 with which the upper ends of links 66 are pivoted, extend vertically upwardly and are, in turn, pivotally connected by pivots 74 (FIG. 6) with projections 75 that project oppositely outwardly of the side frame members of a rectangular, horizontally disposed frame generally designated 76, and which side frame members are indicated at 77. The said projections 75 may be extensions of cross frame members 78 that are adjacent to each end of frame 76, while the end frame members 79 of frame 76 (FIG. 5), are adjacent said cross frame members.

Bars 70 at the ends of frame 76 project upwardly and the upper ends of the pair of bars 70 at each end of the frame are pivotally connected to one of the ends of a pair of rods 80 that extend toward each other from the upper ends of said bars. The inner adjacent ends of the pair of rods 80 that are adjacent each end of frame 76 are pivotally connected at 83, 84 (FIG. 6) to the ends of a link 85 that is centrally secured on a horizontal shaft 86 rotatably carried on cross frame members 78. The link 85 functions as a crank in that rotation of the shaft 86 in one direction will cause the upper ends of bars 70 to swing toward each other so that the lifting bars 60 will be swung outwardly away from each other to dot-dash positions 87 (FIG. 6) while rotation of said shaft in an opposite direction will cause the lifting bars 60 to swing toward each other to engage under a load.

The rotation of said shaft 86 may be effected through a crank arm 88 that is connected at one end thereof with said shaft at a point adjacent to one of the cross frame members 78, while the other end of the crank is pivotally connected with the outer end of a hydraulically actuated piston rod 89 extending from a conventional hydraulic cylinder or gear motor 90 that, in turn, is carried on said cross frame member 78 and is controlled by extensions between it and the operator's cage.

The cables 57 at one end of the carriage and cables 58 at the opposite end extend through relatively large vertically opening eyes 93 on frame 76 to the ends of the lifting bars 60 and, as best seen in FIG. 5, the pair of cables at each end of the frame extend slightly convergently in an upward direction from the lifting bars so that the lifting bars would normally tend to swing toward each other and against the sides of a container, by gravity, when not positively swung apart.

35 The ends of the carriage 29 have depending vertically disposed end plates 94, while the end frame members 79 of frame 76 carry end plates 95. End plates 95 may be offset slightly toward each other relative to the end plates 94 on the carriage 29, but the end plates are in parallel planes.

30 A pair of arms 96 are pivoted at 97 adjacent one of their ends to each of the end plates 95 on frame 76, while a similar pair of arms 98 are pivoted at 99 to the end of each of the end plates 94. The outer ends of said arms are pivotally connected by pivots 100.

35 Toothed segments 101 are respectively rigid with one of the adjacent ends of arms 96, and toothed segments 102 are rigid with the adjacent ends of each pair of arms 98. The arcuate row of teeth on each pair of segments 101, and the arcuate row of teeth on each pair of segments 102 50 are in mesh with each other and each row is concentric with the pivot 97 or 99, thus upon the frame 76 being lowered or elevated the arms 96, 98 will move from horizontally extending collapsed position (FIG. 5) to extended generally vertically extending position (FIG. 4) 55 and at all times these pairs of arms will hold the frame 76 and a container on lifting bars 60 against both side sway and end sway.

It should be noted at this point that the end tendency to 60 sway of the containers is not normally as pronounced as the side swaying due to the fact that the pairs of cables 57, 58 are spaced apart a substantially greater distance than the distance between the cables of each pair, and also the container carried below the frame 76 on lifting bars 60 presents a broadside to the wind, and acts

65 like a sail to cause swinging unless prevented. Furthermore, the inertia of the containers upon being turned about a vertical axis in changing their position from over the railway cars to over the loading area and vice versa, would cause swinging. Obviously arms similar to arms 70 75 may be positioned at one or both opposite sides of the structure, if desired.

In operation, assuming the carriage 29 is suspended from the leg of the overhead Y tracks over the loading 75 platform and the lifting bars and frame 76 are at their

lowermost positions, which would be approximately their positions after unloading a container, and the next container to be removed from a railway car is the farthest removed from the loading platform, the motor 56 will first be actuated to elevate the lifting bars 60 and to collapse the arms 63, 64, 66, 67 sufficiently to enable the lifting bars 60 to clear the tops of cars on the rails closest to the loading platform. It may be necessary in some instances to partially collapse arms 96, 98 to do this, but the operator can readily see when the required elevation is reached. In any event stops 72 rigid on bars 96 (FIG. 5) will limit the collapse of arms 96, 98. Inasmuch as any saving of time and power is a saving of money in the operation, it is apparent that the direct vertical movement of the lifting bars 60 to the desired degree, and no more, will result in a saving.

The operator will then move the gantry crane until the arms of the overhead Y track extend transversely across the container, and the motor 45 on the beam 18 or 31, whichever is farthest from the rails 9, will then be actuated to move the carriage and the lifting bars 60 and frame 76 onto the arms of the overhead Y track, which will occur automatically since the leading beam will move onto the arm that is opposite to the one that is being driven by the motor 45, and as soon as the beams 18, 31 are parallel with each other on the arms of the overhead Y tracks, both motors 45 will drive the carriage to its position over the container that is to be removed.

From the above it is obvious that the relative position between the beams and the carriage determines when the motors 45 will operate simultaneously and when only one will operate and yieldable switch elements respectively on the brackets 44 and on the beams may control such operation. This may be diagrammatically indicated in FIG. 8, in which electrical switch elements 105 on beam 31 and bracket 44 are in engagement, but upon beam 31 swinging toward a position in which it is parallel with the track from which it is supported, the connection is broken and the motor must be independently operated from the control cage. Obviously the operation of the motors may be entirely controlled from the control cage.

The bars 60 are always swung apart when out of engagement with a load, and as soon as the carriage 29 is over the desired container motor 56 is actuated to lower the lifting bars 60 to the point where they will engage below opposite lower corners of the container when the cylinder 90 is actuated to move said bars toward each other. Frame 76 will rest on the container, when the bars are in a position for engaging a load, and the arms 96, 98 will be extended (FIG. 4). The motor 56 will then be actuated to lift the container 35 and it will be lifted to the point where it will clear the tops of the containers 35 intervening between the farthest removed set of rails 9 and the platform 10 upon movement of the carriage 29 toward the leg 17 of the overhead tracks.

Once the container 35 is elevated the desired degree the container will automatically swing to a position substantially at a right angle to the rails 9 and to tracks 1, 2 according to which of the motors 45 is deactivated when the trolley wheels reach the point where the intermediate portions 16 commence, whichever one continues to be engaged will become the leading one, and it will pull the carriage onto the leg portions of the overhead Y and the container will then be parallel with said leg portion where it can be lowered onto the desired trailer or onto the platform. Obviously the gantry crane can be moved if necessary.

By the above arrangement a turntable and its expensive complications is eliminated and the container is stabilized against swinging, and the containers are automatically swivelled so that either end may be turned to the proper position on the trailer or platform.

The reverse of the above operation is readily performed and is obvious, except the end that is nearest to

rails 9 will follow whichever track supports it. However, by running the carriage out onto the legs of the Y the end to end reversal of the carriage can be quickly effected.

5 The employment of the cables in direct lifting relation to the containers and yet the elimination of the swinging of the containers enables the elimination of the heavy and expensive hydraulically actuated arms that have heretofore been employed.

10 FIG. 9 is a greatly reduced and simplified top plan view similar to FIG. 1. In FIG. 9 the frame 3, which may be the same as in the preceding views, carries tracks 111, 112 that are the same as tracks 1, 2, except that the projecting portion 17 of FIG. 1 extends to opposite sides of the frame 3, as indicated at 113. By this structure, loading and unloading of containers or trucks or trailers can be effected at opposite sides of the frame.

15 The carriage 114 in FIG. 9 is the same as carriage 29 in FIG. 1 and by actuating motors 50, 51 in unison when the carriage is suspended from the widely spaced portions of the tracks that are within the confines of the frame, the carriage will move longitudinally of said tracks, but by cutting out one motor or the other by suitable switches at the ends of said widely spaced portions of the tracks, the end that continues to be motorized will lead the outer end onto the end portions of the track, as has been described relative to FIG. 1.

20 In FIG. 10 one track 115 of a pair thereof carried by a frame 116, and which frame is the same as frame 3, is straight from end to end while the other is curved intermediate its end portions as at 117 to space the central portion 118 from track 115 the same distance as the intermediate portions of tracks 1, 2 are spaced apart.

25 By this arrangement the motors 120, 121 on the carriage 122 will function simultaneously to move the carriage along the widely spaced intermediate portion of the tracks, but in motor 120, which is the one at the end of the carriage that is suspended from straight track 115, is the only one that is actuated to move the carriage onto one end portion of the tracks or the other, and motor 121 is the only one that will move the carriage from the end portions of the tracks to the central portion. Thus the carriage in this form of the invention will always have the same leading end in moving to and from the end portions of the tracks.

30 The motor controls may be of any suitable kind, and may be actuated by an operator and automatically by conventional limit switches, except that in FIG. 9, for example, the operator controls whichever one of the motors on the carriage is to be actuated upon movement of the carriage from the central or intermediate portions of the tracks onto the projecting end portions.

35 FIG. 11 is similar to FIG. 5 except that the links 96, 98 have been omitted, as well as their segment connected ends. This arrangement is suitable for lifting loads off trucks, trailers or elsewhere, and stabilizing them against swinging, but in situations where the loads need not be lifted to the same height as in FIG. 2.

40 In all forms of the invention, it should be noted that the multitudinous number of cables heretofore employed, where attempts have been made to extend the cables to the load engaging means, are eliminated. Also the costly and complex turntable structures have been eliminated and the loads that are carried are stable and at the loading and unloading stations at one side of the frame the loads will be automatically positioned in the desired and uniformly correct positions.

45 Where the word "container" is used, it is applicable to a trailer or vehicle that has the containers as a part thereof or separate therefrom.

50 With respect to FIG. 1, it should be noted that the dot-dash line position of the container in which it is intermediate the full line position, and the dot-dash line position below the portions 17 of the overhead tracks may be an unloading and loading position where it is desirable

that the container be at angular positions of, say, approximately 45° relative to the full line position, or at any angle less than 90° relative to said full line position when deposited on a loading platform or when lifted therefrom. It would merely be necessary to widen the loading platform to come below the load, or to extend the intermediate portions 16 of the tracks to extend to a greater degree over the loading platform. This is obvious and in some instances may be desirable, since the carriage suspended from the tracks is quite stable in said position. 10

It is apparent that different embodiments of this invention may be made without departing from the spirit and scope thereof, and therefore, it is not intended to be limited except as indicated in the appended claims. 15

I claim:

1. In a freight container handling apparatus that includes overhead, horizontally extending tracks on a wheel mounted frame and a carriage suspended from said tracks for horizontal movement thereon, the improvement that 20 comprises:

- (a) cable hoisting means on said carriage including a plurality of cables extending downwardly therefrom providing two horizontally spaced pairs thereof and means for winding and unwinding said pairs to raise 25 and lower them, said pairs of cables being adapted to extend downwardly across two opposite sides of a freight container to be lifted upon winding thereof;
- (b) a pair of horizontally extending parallel spaced container engaging members respectively connected 30 with the lower ends of said pairs of cables adapted to engage below said container along said two opposite sides;
- (c) separate relatively rigid vertically extensible and collapsible means carried by said carriage and extending downwardly therefrom and respectively disposed in vertical pairs of planes at right angles to each other in which one plane is at a right angle to said members for holding said members against swinging laterally in directions at a right angle to 40 said members upon actuating said cable hoisting means to elevate said members when the latter are in container engaging relation;
- (d) a horizontally disposed, intermediate frame positioned between said carriage and said members; 45
- (e) one of said vertically extensible means connecting said intermediate frame with said members; and
- (f) the other of said vertically extensible means connecting said intermediate frame with said carriage. 50

2. In a freight container handling apparatus that includes overhead, horizontally extending tracks on a wheel mounted frame and a carriage carried by said tracks for horizontal movement thereon, the improvement that comprises:

- (a) cable hoisting means on said carriage including 55 a plurality of cables extending downwardly therefrom providing two horizontally spaced pairs of horizontally spaced cables, and means for winding and unwinding said pairs to raise and lower them, said pairs of cables being adapted to extend downwardly across two opposite sides of a freight container to be lifted upon winding thereof and with the cables of each pair thereof in spaced relation at each of such sides;
- (b) container engaging means respectively connected 60 with the lower ends of said pairs of cables for releasably engaging said freight container substantially at its lowermost portion along said opposite sides, whereby upon actuation of said cable hoisting means to elevate said container engaging means when the latter are in engagement with substantially said lowermost portion, the weight of said container and the contents thereof will be transmitted directly to said cables at said container engaging means and 65

75

at points at substantially the lowermost portion of said container;

(c) separate relatively rigid anti-sway means disposed between and respectively operatively connected with said carriage and with said container engaging means including relatively rigid vertically extensible and collapsible means disposed in different vertical planes at a right angle to each other for holding said container engaging means, and consequently a container in engagement therewith against swinging laterally upon actuating said cable hoisting means to elevate said container engaging means when the latter are in container engaging position at said points.

3. In a freight container handling apparatus that includes overhead, horizontally extending tracks on a wheel mounted frame and a carriage suspended from said tracks for movement thereon, the improvement that comprises:

- (a) cable hoisting means on said carriage including a plurality of cables extending downwardly therefrom providing two horizontally spaced pairs thereof and means for winding and unwinding said pairs to raise and lower them, and pairs of cables being adapted to extend downwardly across two opposite sides of a freight container to be lifted upon winding thereof;
- (b) a pair of horizontally extending parallel, horizontally spaced container engaging members respectively connected with the lower ends of said pairs of cables adapted to engage below said container along said two opposite sides, said cables being connected with said members at points relatively close to the points of engagement between said members and said container;
- (c) a pair of horizontally spaced, opposed, vertically extensible and collapsible anti-sway means, relatively rigid against side sway, carried by said carriage extending downwardly therefrom toward said container engaging members, and separate means respectively connecting each of said anti-sway means of said pair at the upper end thereof with said carriage, and connecting the lower end thereof with said container engaging means;
- (d) said anti-sway means each including a pair of upper gear segments rotatably supported on said carriage with their teeth in mesh for rotation of said segments together in opposite directions about parallel axes, and a pair of lower gear segments having their teeth in mesh and rotatably supported on the means connecting the lower end of the anti-sway segments with said container engaging means for simultaneous rotation of said lower segments in opposite directions about a parallel axis, an upper pair of links respectively rigid at one of their ends with said upper segments and a lower pair of links respectively rigid at one of their ends with said lower segments and said upper pair of links and said lower pair of links projecting toward each other from said upper and lower pairs of segments and pivotally connected at their outer ends remote from said segments for swinging said pairs of links from generally vertically extending positions to generally horizontally extending positions, and vice versa, upon winding and unwinding said cables for raising and lowering said container engaging means.

4. In freight hoisting and handling apparatus that includes a frame supporting a horizontally disposed overhead carriage having two opposite ends for horizontal movement, and which carriage in turn carries power driven cable winding drums and hoisting cables respectively connected with said drums and depending from said carriage and connected at their lower ends with container engaging means for engagement with a container for lifting such container upon actuation of said drums for winding said cables thereon, the improvement comprising:

- (a) stabilizing means disposed between said container engaging means and said carriage and connected with said carriage and said container engaging means for holding said container engaging means and a container adapted to be engaged thereby against lateral swinging thereof during lifting of said container engaging means and such container by said hoisting cables and during said horizontal movement of said carriage when such container is suspended therefrom, said stabilizing means including: 5
- (b) two pairs of spaced opposed arms at each of said opposite ends of said carriage respectively disposed with one pair above the other thereby providing an upper pair of arms and a lower pair arms at each 15 of said two opposite ends;
- (c) separate pivot means pivotally connecting one of the ends of each upper pair of arms with one of the ends of each lower pair of arms, and pivotally connecting each of the other ends of said upper pair of 20 arms with one of the ends of said carriage, and pivotally connecting the other ends of said lower pair of arms with said container engaging means for movement of said two pairs of arms at said opposite ends of said carriage about parallel horizontal axes 25 only from generally vertically extending extended positions of the pivotally connected upper and lower arms to generally horizontally disposed positions when said cables are actuated to hoist said container engaging means from a lowered position to an elevated position;
- (d) means respectively connecting said other ends of each pair of upper arms and said other ends of each pair of lower arms for positively holding the arms 30

of each of said two pairs against unequal movement relative to the other arms of each of said two pairs during movement of said pairs of arms from said extended positions to said collapsed positions and vice versa;

- (e) said last mentioned means comprising a pair of toothed, arcuately extending segments on said other ends of the arms of each upper pair of arms, and a corresponding pair of toothed, arcuately extending segments on said other ends of the arms of each lower pair of arms, the teeth of the segments of each pair being in intermeshing relation.
